UNITED STATES PATENT OFFICE.

CHARLES SCHMIDLAPP, OF MEMPHIS, TENNESSEE.

DESIGN FOR A CIGAR-BOX.

Specification forming part of Design No. 5,230, dated August 22, 1871.

To all whom it may concern:

Be it known that I, CHARLES SCHMIDLAPP, of Memphis, county of Shelby and State of Tennessee, have invented and produced a new Design for Cigar-Boxes, of which the following is a specification:

Make the cigar-boxes, according to the cigars, so that boxes with only two layers will hold one hundred (100) cigars. By this the cigars will season much faster than in the ordinary way of packing them, and it gives, also, each cigar the direct

benefit of the flavor of the wood out of which the boxes are made. Also, put partitions in the boxes, as shown by the photographic illustration accompanying, by which there can be packed cigars of several different colors in the same box.

I claim as my invention—

The design for a cigar-box, as shown.

CHAS. SCHMIDLAPP.
